(57) **CLAIM**

The ornamental design for a luggage cover, as shown and described.

DESCRIPTION

FIG. 1 is a top and front side perspective view of a luggage cover;

FIG. 2 is a front view of the luggage cover;

FIG. 3 is a rear view of the luggage cover;

FIG. 4 is a first side view of the luggage cover;

FIG. 5 is a second side view of the luggage cover;

FIG. 6 is a top view of the luggage cover;

FIG. 7 is a first bottom view of the luggage cover including a strap in a buckled position; and,

FIG. 8 is a second bottom view of the luggage cover including the strap in an unbuckled position.

The broken lines showing a suitcase depict environment and form no part of the claim. The broken lines that travel across the surface of the luggage cover depict stitching and form no part of the claim. All other broken lines depict portions of the luggage cover and form no part of the claim.

1 Claim, 8 Drawing Sheets
